Primary Examiner — Cynthia M Chin(74) *Attorney, Agent, or Firm* — Akerman LLP

(57)

CLAIMThe ornamental design for a cookware handle, as shown and
described.**DESCRIPTION**FIG. 1 is a perspective view of the “cookware handle,”
showing my new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

The broken lines represent the environment in which the
article resides and portions of the handle that form no part
of the claimed design. None of the broken lines form a part
of the claimed design.**1 Claim, 6 Drawing Sheets**(56)
